UNITED STATES PATENT OFFICE.

FREDERICK PETERS, OF NEWARK, AND WILLIAM THIEDGE, OF ELIZABETH, NEW JERSEY.

CLASP.

Application filed January 18, 1923. Serial No. 613,441.

To all whom it may concern:

Be it known that we, FREDERICK PETERS and WILLIAM THIEDGE, citizens of the United States, the former residing at Newark and the latter at Elizabeth, in the counties of Essex and Union, respectively, and State of New Jersey, have invented certain new and useful Improvements in Clasps; and we do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in clasps; and, the present invention has reference, more particularly, to that class of clasps or fasteners which are designed for use in connection with trousers which are held about the waist or body of the wearer by means of a belt, but which may also be used as scarf or tie-holders, collar-retainers, cuff-holders, and sleeve-holders, and to such other uses where the employment of a holding-clasp is practical.

The present invention has for its principal objects to provide a novel clasp, with a view of producing a neat and ornamental clasp, as well as simplifying its general construction and cheapening the cost of the manufacture of the same, and at the same time providing a strong and efficiently operating construction.

The invention has for its further object to provide a clasp-construction comprising a pair of pivotally connected members, termed hereinafter the upper and lower clamping members, the clamping portions of which are made with outwardly-pressed bridge-pieces, normally in nested or registering relation with each other, and the lower clamping member of which is provided with a resilient clamping or presser-element adapted to be snapped into frictional engagement with the marginal boundary of an opening in the upper clamping member, so that the marginal edge-portion of the said resilient clamping or presser-element will enter into the receiving space directly beneath the bridge-piece of said upper clamping mem-

ber, thereby providing a positive means for clamping and holding the fabric between the said upper and lower clamping members 55 against accidental displacement from between the said bridge-pieces.

A further object of the present invention is to provide an easily operated clasp-construction in which the parts of the clasp 60 when in their clamped relation to the garment, lie flat and close to the material, thus fully eliminating a bulky or clumsy clasp-connection with the fabric or material; and, furthermore, to provide a clasp in which 65 the parts have been reduced to a minimum the parts operating in such a manner that the device may be quickly and easily and positively maintained in its clamped position upon the garment, but being just as 70 easily detached from such clamped or holding relation with the garment.

Other objects of the present invention not at this time more particularly enumerated will be clearly understood from the following detailed description of the present invention.

With the various objects of the present invention in view, the said invention consists, primarily, in the novel clasp hereinafter set forth; and, the said invention consists, furthermore, in the novel arrangements and combinations of the several devices and parts, as well as in the details of the construction of the said parts, all of which will be more fully described in the following specification, and then finally embodied in the clauses of the claims, which are appended to and which form an essential part of the said specification.

The invention is clearly illustrated in the accompanying drawings, in which:—

Figures 1 and 2 are views of the clasp embodying the principles of the present invention, Figure 1 showing the use of the 95 clasp as a trouser-support, and Figure 2 illustrating the clasp in its use as a shirt-sleeve holder.

Figure 3 is a front face view, on an enlarged scale, of the clasp represented in said Figure 1, said view showing a fragmentary portion of the waist-band of a garment and a portion of the wearer's shirt, with both of which the device is used as a garment-sup-

porter; and Figure 4 is a vertical sectional representation of the several devices and parts represented in said Figure 3, said section being taken on line 4—4 in said Figure 3.

Figure 5 is a rear face view of the clasp shown detached from the waist-band of the garment and from the shirt; and Figure 6 is a vertical sectional representation of the 10 same, said section being taken on line 6—6 in said Figure 5.

Figure 7 is a transverse sectional representation of the clasp, said section being represented as being taken on line 7—7 in said 15 Figure 5; and Figure 8 is a reverse face view of the lower clamping member from that of the same member represented in said Figure 5.

Figure 9 is a front face view of a pair of 20 clasps made according to and embodying the principles of the present invention, the two clasps being connected by a piece of webbing, or the like, to adapt the device to the sleeve of a shirt, as a sleeve-holder; Figure 10 is a vertical sectional representation of the devices and parts represented in said Figure 9, said section being taken on line 10—10 in Figure 9; and Figure 11 is a rear face view of one of the clasps, and a portion 25 of the webbing attached thereto, shown in said Figures 9 and 10.

Similar characters of reference are employed in all of the said above described views, to indicate corresponding parts.

Referring now more particularly to Figures 1 to 8 inclusive of the drawings, the reference-character 1 indicates a complete clasp, showing one embodiment of the principles of the present invention, the same 30 comprising an upper clamping member 2 and a lower clamping member 3, both of which may be of any desired marginal configuration, as will be clearly evident. The said clamping member 2 is made with a 35 pivot-plate or element, as 4, with which is connected a suitably formed fingerpiece 5. Similarly, the clamping member 3 is made with a pivot-plate or element, as 6, which terminates in an extension, as 7, and which 40 provides the other finger or thumb-piece of the clasp. As shown, these pivot-plates 4 and 6 are respectively provided with marginal pivot-ears or pintle-receiving lugs 8 and 9 in registration with each other, the 45 respective ears or lugs being connected by means of the usual pintle 10 and the usual actuating-spring 11 encircling the same, and for the purpose of providing the normal clamping movement of the said clamping 50 members 2 and 3 toward each other, as will be clearly understood from an inspection of the several figures of the drawings. As shown, the outer clamping member 2 is formed with an outwardly pressed portion, 55 said portion providing a bridge-piece 12, be-

neath which is a receiving space 13 bounded by the cut portions 14 and 15 and the connecting end-walls 16, between the bridge-piece 12 and the body of the clamping member 2, substantially as illustrated in Figure 6 of the drawing. Similarly, the lower clamping member is also formed with a pressed-out portion, providing a second bridge-piece 17, adapted to normally project into the above-mentioned receiving space 13. 75

As shown in said Figure 6, and more particularly in Figures 5 and 8 of the drawings, the width of the said bridge-piece 17 is less than that of the bridge-piece 12, so that the said clamping member 3 will 80 be provided with a laterally extending opening 18, substantially as shown. Secured to the back of the said bridge-piece 17, along the metal portion lying directly above the said opening 18, by means of rivets 19, or 85 in any other manner, is a plate or bar 20 formed along one of its longitudinally extending marginal edges with a forwardly extending member 21, which is preferably curved, as at 22, said member projecting into 90 the opening 18 and in frictional engagement with the previously-mentioned edge-portion 14 of the clamping member 2, substantially as shown in said Figure 6 of the drawings, the said member 21 acting in the manner of 95 a resilient or yieldable spring-tongue, adapted to be snapped past the said edge-portion 14, when the two clamping members 2 and 3 are brought into their closed relation by the action of the spring 11, as will 100 be clearly understood.

When the clasp is to be used as a means for holding up a pair of trousers, or other garment, the previously mentioned extension 8 of the lower clamping member 3 is 105 provided along its marginal edges with grasping or clamping elements, as 23, by means of which the free ends 25 of an elastic cord 24, or the like, are secured to said extension 7, the said cord being looped, so 110 as to provide an eye 26, which is adapted to be placed about the usual button 27 with which the waistband 28 of the garment is usually provided. This having been accomplished, the hinged or pivotally connected 115 clamping members 2 and 3 are brought into their separated or opened relation, by the application of pressure upon the two finger-pieces 5 and 7, whereby the bridge-member 17 is withdrawn from the space 13 beneath the bridge-piece 12, as will be clearly evident. The shirt of the wearer is thereupon bunched, as at 29, see Figures 1, 3 and 4 of the drawings, said bunched portion of the shirt thereupon being placed between the 120 separated or opened clamping members 2 and 3. By then closing these members upon said inserted portion 29 of the shirt, the registering bridge-pieces 12 and 17, as 125 well as the binding action exerted by the re- 130

silent or yieldable spring-member 21 and the marginal edge-portion 14 of the member 2, will positively retain the clasp in its operative relation with the bunched portion 5 29 of the shirt, or the like.

As has been previously stated, the herein-described clasp is applicable to many uses, being adapted for use as a scarf-holder, cuff-holder, hose-supporter, and the like, and in 10 Figures 2, 9, 10 and 11, we have shown the use of the clasp as a sleeve-holder.

In that case, two clasps 1 of the construction herein-above described are attached to the ends of a suitable webbing 30, or the like, the clasps being used in the manner previously set forth, for grasping the portions 31 and 32 of the sleeve, as will be clearly understood from an inspection of 15 said Figures 2, 9 and 10 of the drawings.

20 We are aware that changes may be made in the various arrangements and combinations of the several parts of the device without departing from the scope of the present invention. Hence we do not limit our invention to the exact arrangements and combinations of the parts as herein described and as illustrated in the accompanying drawings; nor do we confine ourselves to the exact details of the construction of the said parts.

Having thus described our invention, what we claim is:—

1. A clasp comprising a pair of hinged and spring-controlled clamping members, 35 each member being provided with an open portion and an outwardly extending bridge-piece located above said open portion, the bridge-piece of one of said clamping members being adapted to enter into a receiving 40 space located directly beneath the bridge-piece of the other clamping member.

2. A clasp comprising a pair of hinged and spring-controlled clamping members, each member being provided with an open 45 portion and an outwardly extending bridge-piece located above said open portion, the bridge-piece of one of said clamping members being adapted to enter into a receiving space located directly beneath the bridge- 50 piece of the other clamping member, and a yieldable spring-member also connected with one of said clamping members and extending upwardly into the receiving space beneath the bridge-piece of the other clamping 55 member.

3. A clasp comprising an upper clamping member and a lower clamping member, a means of pivotal connection between said clamping members, a spring for normally 60 forcing said clamping members in clamping engagement, finger-pieces connected with and extending from said clamping members for separating said clamping members, said upper clamping member being provided with an opening and with an outwardly 65

extending bridge-piece located above said open portion, said lower clamping member being likewise provided with an opening and with an outwardly extending bridge-piece located above said opening, said latter 70 bridge-piece being adapted to enter into a receiving space located directly beneath the bridge-piece of said upper clamping member.

4. A clasp comprising an upper clamping member and a lower clamping member, a means of pivotal connection between said clamping members, a spring for normally 75 forcing said clamping members in clamping engagement, finger-pieces connected with and extending from said clamping members for separating said clamping members, said upper clamping member being provided with an opening and with an outwardly extending bridge-piece located above said open portion, said lower clamping member being likewise provided with an opening and with an outwardly extending bridge-piece located above said opening, said latter bridge-piece being adapted to enter into a receiving space located directly beneath the bridge-piece of 80 said upper clamping member, the width of the bridge-piece of the lower clamping member being less than the width of the bridge-piece of the upper clamping member, and a yieldable spring-member, connected with said lower clamping member and extending upwardly past the bridge-piece of said lower clamping member and into the receiving space beneath the bridge-piece of the upper 85 clamping member.

5. A clasp comprising an upper clamping member and a lower clamping member, a means of pivotal connection between said clamping members, a spring for normally 90 forcing said clamping members in clamping engagement, finger-pieces connected with and extending from said clamping members for separating said clamping members, said upper clamping member being provided with an opening and with an outwardly extending bridge-piece located above said open portion, said lower clamping member being likewise provided with an opening and with an outwardly extending bridge-piece located 95 above said opening, said latter bridge-piece being adapted to enter into a receiving space located directly beneath the bridge-piece of said upper clamping member, the width of the bridge-piece of the lower clamping member being less than the width of the bridge-piece of the upper clamping member, and a yieldable spring-member comprising a plate mounted upon the back of said lower clamping member, said plate having a forwardly extending member provided along its marginal edge with a curved portion, said forwardly extending member and curved edge-portion projecting into the receiving space beneath the bridge-piece of 100

said upper clamping member, and normally being in frictional contact with one of the marginal edge-portions bounding the opening in said upper clamping member.

5 6. A clasp comprising an upper clamping member and a lower clamping member, a means of pivotal connection between said clamping members, a spring for normally forcing said clamping members in clamping engagement, finger-pieces connected with and extending from said clamping members for separating said clamping members, said upper clamping member being provided with an opening and with an outwardly extending bridge-piece located above said open portion, said lower clamping member being likewise provided with an opening and with an outwardly extending bridge-piece located above said opening, 10 said latter bridge-piece being adapted to enter into a receiving space located directly beneath the bridge-piece of said upper clamping member, combined with an elastic cord formed with a button-receiving loop, and means connected with said lower clamping member for securing the free end-portions of said elastic cord to said lower clamping member.

7. A clasp comprising an upper clamping member and a lower clamping member, a means of pivotal connection between said clamping members, a spring for normally forcing said clamping members in clamping engagement, finger-pieces connected with and extending from said clamping members for separating said clamping members, said upper clamping member being provided with an opening and with an outwardly extending bridge-piece located above said open portion, said lower clamping member being likewise provided with an opening and with an outwardly extending bridge-piece located above said opening, said latter bridge-piece being adapted to enter into a receiving space located directly beneath the bridge-piece of said upper clamping member, the width of the bridge-piece of the lower clamping member being less than the width of the bridge-piece of the upper clamping member, and a yieldable spring-member connected with said lower clamping member and extending upwardly past the bridge-piece of said lower clamping member and into the receiving space beneath the bridge-piece of the upper clamping member, combined with an elastic cord formed with a button-receiving loop, and means connected with said lower clamping member for securing the free end-portions of said elastic cord to said lower clamping member.

8. A clasp comprising an upper clamping member and a lower clamping member, a means of pivotal connection between said clamping members, a spring for normally

forcing said clamping members in clamping engagement, finger-pieces connected with and extending from said clamping members for separating said clamping members, said upper clamping member being provided with an opening and with an outwardly extending bridge-piece located above said opening, said latter bridge-piece being adapted to enter into a receiving space located directly beneath the bridge-piece of said upper clamping member, the width of the bridge-piece of the lower clamping member being less than the width of the bridge-piece of the upper clamping member, and a yieldable spring-member, comprising a plate mounted upon the back of said lower clamping member, said plate having a forwardly extending member provided along its marginal edge with a curved portion, said forwardly extending member and curved edge-portion projecting into the receiving space beneath the bridge-piece of said upper clamping member, and normally being in frictional contact with one of the marginal edge-portions bounding the opening in said upper clamping member, combined with an elastic cord formed with a button-receiving loop, and means connected with said lower clamping member for securing the free end-portions of said elastic cord to said lower clamping member.

9. A clasp comprising an upper clamping member and a lower clamping member, a means of pivotal connection between said clamping members, a spring for normally forcing said clamping members in clamping engagement, finger-pieces connected with and extending from said clamping members for separating said clamping members, said upper clamping member being provided with an opening, and a yieldable spring-member connected with said lower clamping member and extending upwardly into the opening in said upper clamping member into frictional contact with one of the marginal edge-portions bounding the opening in said upper clamping member.

10. A clasp comprising an upper clamping member and a lower clamping member, a means of pivotal connection between said clamping members, a spring for normally forcing said clamping members in clamping engagement, finger-pieces connected with and extending from said clamping members for separating said clamping members, said upper clamping member being provided with an opening, and a yieldable spring-member, comprising a plate mounted upon the back of said lower clamping member, said plate having a forwardly extending member provided along its marginal edge

with a curved portion, said upwardly extending member and curved edge-portion projecting into the opening in said upper clamping member into frictional contact with one of the marginal edge-positions 5 bounding the opening in said upper clamping member.

In testimony, that we claim the invention

set forth above we have hereunto set our hands this 10th day of January, 1923.

FREDERICK PETERS.
WILLIAM THIEDGE.
